UNITED STATES PATENT OFFICE.

ARTHUR OWEN JONES, OF WHITLEY BAY, ENGLAND, ASSIGNOR OF ONE-HALF TO
THE FIRM OF STETTINER CHAMOTTE-FABRIK ACTIEN-GESELLSCHAFT VORMAEL
DIDIER, OF STETTIN, GERMANY.

VERTICAL COKE-OVEN.

1,028,569.

Specification of Letters Patent.

Patented June 4, 1912.

Application filed July 15, 1911. Serial No. 638,625.

To all whom it may concern:

Be it known that I, ARTHUR OWEN JONES, a subject of the King of Great Britain, residing at Whitley Bay, in the county of 5 Northumberland, England, have invented certain new and useful Improvements in Vertical Coke-Ovens, and of which the following is a specification.

This invention relates to improvements in 10 the construction of vertical coke ovens, whereby the length of the heating flues is shorter than hitherto, and a more efficient coking action within the coking chambers is obtained.

15 According to this invention, each side wall of the coking chambers is provided with a plurality of superposed horizontal heating flues, which extend from end to end thereof, and the oven structure is formed at each 20 end of each side wall with a vertical passage, which communicates with a regenerative chamber at the respective side of the oven structure, so that heated air from the regenerative chamber at one side of the oven 25 structure, passes up the vertical passage communicating therewith, and through the horizontal heating flues (where it meets combustion gases as is well known), to the other end of said heating flues, down the vertical 30 passage at that side of the structure, and into and through the regenerative chamber located at that side.

On the drawings, Figures 1 and 1^A combined show a vertical section taken through 35 the side wall of an oven, Fig. 2 being a similar view of a portion drawn to a larger scale, while Fig. 3 is a horizontal section showing two ovens and the passages aforesaid in the side walls, the central portion of 40 the structure in each case being broken away.

Referring to the accompanying drawings, the horizontal flues 1 in the side walls 2 of the ovens 3 extend from the side walls 4, 5 of the oven structure and are arranged 45 one above another, there being, in the construction shown particularly at Fig. 3, two vertically superposed series of such heating flues 1, one series adjacent to one oven and the other series adjacent to the other oven, 50 both series being as shown formed in the same side wall. Formed in or adjacent to the side walls 4, 5 and at the end of each side wall 2 there are vertical flues 6, 7 with which all the horizontal heating flues 1, in

the side wall 2 communicate, and valves 8, 55 operated from the exterior of the structure by handles such as 9, are fitted by which any particular horizontal flue 1 can be shut off from communication with either or both of the vertical flues 6, 7. For each horizontal heating flue 1 there are fitted two gas supply nozzles 10, 11 one communicating with one end of a flue 1 and the other gas nozzle 11 with the other end of the same flue and means, not necessary to illustrate in the 60 drawings, are provided such as a cock or the like whereby any individual gas supply nozzle can be cut off.

Referring more particularly to Fig. 1 the vertical flue 6 communicates with a regenerative chamber 12, constructed in any well known manner, which chamber communicates at will by means of any suitable valves either with a common uptake for the products of combustion or with the open 70 air. Similarly as shown in Fig. 1^A the vertical flue 7 communicates with a regenerative chamber 13. With such an arrangement gas is supplied by for instance the nozzles 10 at one end of the structure to the horizontally extending heating flues 1 and at the same time the valves 8 are opened and heated air passes thereby from the vertical 75 heated air supply passage 6 to the said horizontal flues 1, such air being drawn from the regenerative chamber 12 which has previously been employed for the passage of the products of combustion and is therefore in a heated state. The products of combustion 80 then pass through the horizontally extending heating flues 1 in the side walls 2 of the oven and at the opposite ends such products pass down the vertical flue 7 which at this time acts as the exit flue, and by way of this 85 vertical flue 7 the products of combustion 90 pass to the regenerative chamber 13 outside the structure of the oven and adjacent to the side walls of said structure and from thence to the uptake not shown in the drawing. It 95 will be observed that when working in this manner any particular horizontal flue 1 or any desired number of such flues can be thrown out of operation by adjusting the valves 8 and this without detrimentally affecting any of those horizontal flues 1 which 100 it is desired shall continue in work. After the ovens have been at work in this manner for a period, the regenerator 13 is placed in

communication with the open air and the re-generator 12 in communication with the uptake, while at the same time the gas supply nozzles 10 are closed and the gas supply nozzles 11 are opened, and the course of the products through the flues is thus changed, the air being drawn from that regenerator which was previously employed for the passage of the heated products.

- 10 Although in the example of construction I have shown each oven (or the heating flues in each side wall of an oven) as being served by two regenerative chambers one at each side of the oven and which arrangement I believe is particularly advantageous, yet I would have it understood that in some cases I may employ a regenerative chamber at each side of a set of ovens to serve the flues in the side walls of more than one oven.
- 15 20 It will be obvious that instead of employing a set of superposed heating flues each of which has two arms arranged in a horizontal plane in each side wall, (see Fig. 3) the arms of the said heating flues may be arranged in a vertical plane and be utilized in a wall dividing two ovens to heat the adjacent sides of the two ovens.
- 25 30 What I claim as my invention and desire to secure by Letters Patent is:—

- 30 1. Coking ovens, comprising in combination vertical coking chambers surrounded by end and side walls, each side wall having a plurality of horizontal superposed heating flues extending through said side wall from end to end thereof, each end of each side wall having a vertical passage, regenerative chambers connected to said vertical passages and communicating therewith, means for

admitting gas to said horizontal heating flues at each end thereof, and means for controlling the passage of products of combustion through one or more of the horizontal heating flues independent of the other flues.

2. Coking ovens, comprising in combination vertical coking chambers surrounded by end and side walls, each side wall, which forms a partition between two adjacent coking chambers, having a series of superposed horizontal heating flues extending through said side wall from end to end thereof and in a vertical plane in proximity to the side of one of the coking chambers, and a second series of superposed horizontal heating flues extending through said side wall from end to end thereof, in proximity to the adjacent coking chamber and in a plane parallel to the vertical plane containing the other series of horizontal heating flues, each end of each side wall having a vertical passage connected to the corresponding end of each horizontal heating flue, regenerative chambers connected to said vertical passages and communicating therewith, and means for admitting gas to horizontal heating flues at each end thereof, and means for controlling the passage of products of combustion through one or more of the horizontal heating flues independent of the other flues.

In witness whereof I have hereunto set my hand in the presence of two witnesses.

ARTHUR OWEN JONES.
